CLAIM

The ornamental design for a myofascial release apparatus as shown and described.

DESCRIPTION

FIG. 1 is a front view of a myofascial release apparatus showing the new design;

FIG. 2 is a rear view thereof;

FIG. 3 is a top view thereof;

FIG. 4 is a bottom view thereof;

FIG. 5 is a right side view thereof; and,

FIG. 6 is a left side view thereof.

Any broken lines in the drawings are for the purpose of illustrating portions of the article that form no part of the claimed design.

1 Claim, 5 Drawing Sheets(56)
